(57) **CLAIM**

The ornamental design for container and cap, as shown and described.

DESCRIPTION

FIG. 1 is a top perspective view of a first embodiment of a container and cap according to the present invention; FIG. 2 is a bottom perspective view of the lower portion of a container and cap thereof;

FIG. 3 is a side elevational view of FIG. 1;

FIG. 4 is a top plan view thereof;

FIG. 5 is a bottom plan view thereof;

FIG. 6 is a top perspective view of a second embodiment of a container and cap according to the present invention;

FIG. 7 is a side elevational view thereof;

FIG. 8 is a top plan view thereof;

FIG. 9 is a top perspective view of a third embodiment of a container and cap according to the present invention;

FIG. 10 is a side elevational view thereof;

FIG. 11 is a top plan view thereof;

FIG. 12 is a top perspective view of a fourth embodiment of a container and cap according to the present invention;

FIG. 13 is a side elevational view thereof; and,

FIG. 14 is a top plan view thereof.

The bottom surface of the container and cap in embodiments 2-4 is identical to the bottom surface as shown in FIGS. 2 & 5.
